UNITED STATES PATENT OFFICE.

EARL G. WATROUS, OF CHICAGO, ILLINOIS.

LAVATORY SUPPORT.

Application filed July 26, 1926. Serial No. 124,997.

This invention relates more particularly to lavatories for use in railway cars and to means for properly supporting the same. Heretofore such lavatories have usually 5 been made of metal but they have been found objectionable and the use of lavatories formed of ceramic material has been suggested. The advantages of lavatories formed of porcelain or the like are well understood, 10 but attempts to use the same in railway cars have not proven successful. Such ceramic bowls or lavatories are comparatively heavy and are comparatively frangible or easily cracked or broken. On account of the ex- 15 cessive changes in temperature to which these lavatories are subjected in railway cars as well as the jarring and strain incident to the movement and stopping of the cars, porcelain lavatories when mounted in the usual 20 manner are likely to soon become broken.

In accordance with the present invention, I provide a ceramic lavatory with novel means for mounting the same so that it is adapted for use in railway cars or other ve- 25 hicles.

The objects of this invention are to provide an improved lavatory and method of mounting the same; to provide an improved bracket for supporting a lavatory; to provide means 30 for cushioning a lavatory on the bracket; and to provide such other advantages and novel features as will be described more fully hereinafter.

In the accompanying drawings illustrating 35 this invention;

Figure 1 is a side view;

Figure 2 is a longitudinal sectional view of the bracket and adjacent portions of the lavatory; and

Figure 3 is a sectional view taken on the line 3—3 of Figure 2.

The porcelain or earthen-ware lavatory 4, shown in these drawings, is intended to represent any suitable type such as are adapted 45 to fit against a side wall or in a corner. This lavatory may be fitted with any ordinary or preferred fittings or connections, but as they form no part of the present invention, further description is omitted.

In the present instance, the lavatory 4 is supported on a wall 5 by means of brackets 6. These brackets are secured to the wall by means of bolts or screws 7 which hold them firmly in position. Each bracket comprises 50 a back plate or portion 8 with an outwardly projecting plate or flange 9. This flange is

preferably provided with a lower strength- 60 ening rib 10, and has an upper rib 11 which engages with a slot or recess 12 in the lower surface 13 of the lavatory. The rib or pro- 65 jection 11 extends to the back of the bracket but may terminate a short distance from the outer end of the bracket in order to provide a shoulder 13 which engages with the shoulder 14 at the end of the slot. This leaves a small 70 portion of the upper surface of the bracket beyond the rib, as indicated at 15, for sup- 75 porting the opposed surface of the lavatory. The engaging or supporting portion of the lavatory may be the usual top portion, com- 80 monly known as a slab or as illustrated may comprise a downwardly extending peripheral projection 16 which is formed integrally with the lavatory. A coating or layer 17 of putty, cement, or the like is preferably placed be- 85 tween the bracket and engaging portion of the lavatory and the parts are then drawn to- 90 gether and the lavatory held in position by bolts 18. These bolts extend through slots 19 in the lavatory and holes 20 in the brackets 95 and are provided with nuts 21. For conven- 100ience in installation, such bolts are prefer- 105 ably provided with T heads. The outer por- 110tion of the lavatory may also be provided with braces 22 for further supporting the

same. The slot or recess 12 is shown in Figure 2 as being somewhat longer than the rib or lug 11, but it is apparent that this slot may be made as long as desired in order to pro- 115 vide for longitudinal adjustment or fitting 90 of the lavatory on the bracket. This is de- 120sirable as these lavatories being made of por- 125celain or the like are apt to vary more or less in size. If desired, this slot may also be ex- 130tended upwardly through the bottom plate 95 of the lavatory or slot 19 extended to coin- 135cide in length with the slot 12. It will be noted that when the parts are 140 fastened together, as particularly shown in Figures 2 and 3, the brackets not only serve 100 to support the weight of the lavatory but on account of the upwardly projecting ribs or 145 projections which fit in the slots or recesses, 150 serve to take any sidewise or lateral thrust 155 such as is apt to be caused by starting and 160 stopping of the car. When such bowls are 165 mounted on the side walls, the brackets pro- 170ject transversely with respect to the car so 175 that such thrust is taken throughout the full 180 length of the ribs, and from actual use I have 185 found that there is little or no liability of the 190 lavatory becoming cracked or broken. The

putty or cementitious material 17 further serves to cushion the bowls or lavatories against shock and jar and also tends to fill any spaces between the lavatory and the 5 brackets so as to insure full contact throughout various opposed surfaces.

It will be apparent that the parts may be modified in order to adapt the construction for different conditions or positions, and 10 therefore I do not wish to be limited to the exact arrangement herein shown and described, except as specified in the following claims, in which

I claim—

15 1. The combination of a plurality of wall brackets having vertical portions for engagement with the wall and horizontal portions for supporting a lavatory, means for securing the brackets to the wall, said brackets 20 having longitudinal ribs on the upper faces thereof which are shorter than the upper faces, a lavatory having slots in the lower surface thereof for receiving said ribs, said slots having shoulders at their inner ends for 25 engagement with the ends of ribs, a cementitious filling material between the lavatory and the brackets, and bolts extending through the brackets and adjacent portions of the lavatory.

30 2. A wall bracket for a lavatory, having a

flat upper surface, and having an integrally formed rib which is shorter than the bracket projecting upwardly from said surface.

3. A wall bracket comprising a vertical wall engaging portion and a horizontal lavatory supporting portion, said horizontal portion having a substantially flat upper surface with a rib extending upwardly and terminating a short distance from the end of the bracket to provide an end abutment, substantially as described.

4. In a lavatory mounting for railway cars, the combination of a lavatory having slots in its lower surface, supporting brackets having arms engaging with said lower surface, said arms being provided with ribs for engagement with the slots, and means for securing the lavatory to the brackets.

5. The combination with a lavatory for railway cars, having flat supporting surfaces with recesses therein, of brackets adapted to be secured to the wall of the car and having outwardly projecting plates engaging with the lower surfaces of the lavatory, said plates having ribs fitting in said recesses, plastic material interposed between the brackets and the lavatory, and bolts for fastening the lavatory to the brackets.

EARL G. WATROUS.
